UNITED STATES PATENT OFFICE.

CHARLES W. DYSON, OF UNITED STATES NAVY, AND MILTON C. STUART, OF ANNAPOLIS, MARYLAND, ASSIGNEES TO ANDALE ENGINEERING COMPANY, OF PHILADELPHIA, PENNSYLVANIA, A CORPORATION OF PENNSYLVANIA.

EVAPORATOR.

Original application filed March 26, 1920, Serial No. 369,114. Divided and this application filed August 10, 1922. Serial No. 580,990.

To all whom it may concern:

Be it known that we, CHARLES W. DYSON, rear admiral, United States Navy, and MILTON C. STUART, both citizens of the United States, respectively residing at Washington, District of Columbia, and Annapolis, county of Anne Arundel, State of Maryland, have invented certain new and useful Improvements in Evaporators; and we do hereby declare the following to be a full, clear, and exact description of the invention, such as will enable others skilled in the art to which it appertains to make and use the same.

This invention relates to evaporators, especially adapted for use aboard ships, and has for its object to provide a means for this purpose which will be comparatively inexpensive to manufacture and more efficient in action than those heretofore proposed.

With these and other objects in view, the invention consists in the novel details of construction and combinations of parts more fully hereinafter disclosed and particularly pointed out in the claims.

This application is a division of our pending application for "evaporators," filed March 26, 1920, Serial No. 369,114, now Patent Number 1,440,723.

Referring to the accompanying drawings forming a part of this specification, in which like numerals designate like parts in all the views:

Figure 1 is a diagrammatic elevational view partly in section of a first effect evaporator joined to a second effect evaporator made in accordance with this invention;

Figure 2 is a sectional plan view of the second effect evaporator shown in Figure 1;

Figure 3 is a side elevational view, partly in section, of the second effect evaporator shown in Figure 2;

Figure 4 is a detail sectional view illustrating one of the coiled tubes in position;

Figure 5 is a plan view of the parts shown in Figure 4;

Figure 6 is an enlarged sectional detail view of one of the drain plugs;

Figure 7 is a sectional view of a micrometer valve employed in this invention; and

Figure 8 is a sectional view taken on the line 8—8 of Figure 7, looking in the direction of the arrows.

Referring particularly to Figure 1, the numeral 1 indicates the outer shell of a first effect evaporator, 2 a high pressure steam pipe, leading directly from the boilers, not shown, 3 a micrometer valve illustrated in detail in Figures 7 and 8, 4 a drain pipe provided with a micrometer valve 5, and 6, 7, 8, 9, 10, 11 and 12 indicate partitions between the outer wall 13 and the inner wall 14 of the door like members 15 with which the first effect evaporator 1, as well as the second effect evaporator 54 are provided. One of these said door like members 15 is conveniently secured to the shell 54 as at 16, and the other is secured in a similar manner, not shown, to the first effect shell 1.

On the interior of each of the shells 1 and 54 of the evaporators, there are provided a plurality of steam conveying coiled tubes. These tubes may be as numerous as desired, and are preferably arranged in horizontal rows. Three of the top rows of these tubes are numbered 17, 18, and 19, and are best shown in Figures 2 and 3. The open ends of each of the tubes communicate with channels that are formed in the doors 15 separated by the partitions numbered 6 to 12. The top channels in the evaporators 1 and 54 are numbered 20, the next lower channels are numbered 21 and the next succeeding channels are numbered 22. That is to say, as will be understood from Figures 3, 4 and 5, a given coil or tube has its upper end 23 opening into an upper channel such as 20 above a partition such as 6, and the lower end 24 of said tube opens into a lower channel such as 21 below said partition 6. But, as above stated, it is preferred to provide for each of the channels 20 and 21 a plurality of coils or convolutions as best indicated in Figure 2, and in such case, all their upper open ends 23 will be joined in parallel with an upper channel while all their lower ends will be joined in parallel with a lower channel.

On the other hand, said channels or steam coil elements 6 to 12 have no communication with each other except through drain orifices and said coiled tubes.

It therefore follows that if we count, from the top row down, the said convolutions or coils or tubes are joined in series, as will be

evident when we note that the steam entering the ends 23 of the coil 17 for example, in the channel 20, will be discharged from the ends 24 of said coils 17, into the next 5 lower channel 21, whence the said steam immediately enters the upper ends of the coils 18, and discharges from the lower ends of said coils into the succeeding lower channel 22 and so on down to the last channel in 10 the first effect 1, or in the second effect 54. The coils or tubes are firmly held in position by their ends being rolled or expanded into the walls 14 of each of the doors 15, and are attached at their rear portions to 15 a plurality of braces 27, some of which are preferably provided with the flanged plates 270, see Figures 2 and 3, and which braces are secured to the doors 15 by the tie rods 28 as illustrated. So firmly do said braces 20 and tie rods hold the coils that the rear portions of the latter are not moved to any substantial extent upon changes in temperature, and therefore, movements due to expansions and contraction are taken up by 25 the convolution of the coils, as will presently appear. As above stated, the steam passes through the coils in each channel in multiple, and passes through said coils, when considered in vertical rows in series, but as 30 the steam flows through the successive coils, part of it is condensed in each coil, due to the loss of heat to the water being evaporated, in the spaces 29 of each evaporator 1 and 54. In order to drain off this 35 condensed steam there is provided in each channel 6 to 12 the drain plug 30, as best shown in Figures 1 and 6. Each plug is provided with a hole 31, so small that no appreciable amount of live steam can escape there- 40 through, while at the same time the condensed steam or water can be forced through said hole by the pressure of the live steam in the coils, said plugs 30 are preferably located in depressions 32 provided in the 45 channels, so that a water seal 33 formed by said condensed steam will usually overlie each hole 31. A plug 34 for cleaning and inspection purposes may be provided over each plug 30 as illustrated.

50 It will be clear that the condensed steam through each plug 30 will drain into the channel next below, until it reaches the drain pipe 4. Not only may high pressure steam be utilized in the first effect evaporator 1, 55 through pipe 2, but exhaust steam from any convenient source or sources may be led in through pipe 37 provided with the micrometer valve 38 when it is not desired to use high pressure steam. In either case, the 60 steam supply to the evaporator may be so regulated by adjusting the micrometer valves 3 and 5 (as will be presently explained); that it is substantially all condensed in the coils, and therefore, only condensed steam passes out the drain pipe 4,

or if any live steam should pass into the pipe 4, the micrometer valve 5 may be so adjusted as to prevent it, as will likewise be explained below.

The construction of the micrometer valves 3, 5, and 38, as well as others which will be mentioned hereinafter, will be clear from Figures 7 and 8, wherein 39 represents a steam passage to be controlled, 40 a disk movable across said passage, and provided 70 with the expanding curved crescent shaped slot or opening 41 adapted to adjustably throttle said passage. 42 represents a stem on which said disk is mounted, 43 a graduated disk, 44 a pointer, coacting with the 75 graduations on the disk 43, and 45 means for moving said pointer over said disk 43. It is evident that by properly adjusting the pointer 44, any desired proportion of the area of the passage 39 can be cut off and 80 therefore, the steam may be throttled with certainty to any desired degree. The peculiar curvature of the tubes or coils such as 17, 18 and 19 in both the first and second effect evaporators constitutes an important 85 feature of this invention in that said curvature causes a more efficient scaling action than does other forms of curvature. That is to say, said coils being immersed in sea water, the well known scale, due to such 90 water, soon forms thereon but owing to each coil being continuously curved and reversely curved from end to end, without having any straight portions at all, it is evident that any expansions or contractions, 95 due to changes in temperature will aid in frequent loosenings of the scale at every point of each coil. The scale loosening effect is further multiplied by securing the coils firmly against bodily movement by 100 means of the braces and rods 27 and 28, as above explained. In other words, owing to the peculiar curvature of these said coils they can be made very much longer than heretofore, and a relatively slight change in 105 temperature will produce a relatively large movement, or change, in curvature of said coils, and thus the scale is broken off with a frequency and an efficiency heretofore un- 110 attained.

115 The vapor from the salt water in the first effect evaporator 1 may pass off through the pipe 45, having the micrometer valve 46, to the distiller, not shown. Or, all or a portion of said vapor may pass through the 120 pipe 48 having the micrometer valve 49, to the vapor separator 50, wherein any salt water vapor present may be extracted. From the separator 50, the pipe 51 conveys said distilled vapor through the micrometer valve 52, to the chamber or channel 20 of the said second effect evaporator 54. Said second effect or lower pressure evaporator 54 is constructed substantially like the first effect evaporator and therefore duplicate 125 130

parts in each evaporator are designated, by similar numerals.

The operation of said second effect evaporator is similar to said first effect apparatus, the main differences being the provision of the partition 53 which separates the vapor delivered through the pipe 51 from that delivered through pipe 55, as will presently appear. The vapors from the sea water contained in the space 29 of said second effect evaporator may be carried off by any suitable means similar to the pipe 45', in the first effect evaporator, but is not illustrated.

It is evident, however, that vapors coming through the pipe 51 into the second effect evaporator may be so controlled by the micrometer valve 52 that they will all be substantially condensed by the time they reach the channel 57, in said second effect evaporator whence their condensate may be drained off through the micrometer valve 58 and pipe 59 to the distillers. It thus results that whether the evaporated sea water is led directly to the distillers through the pipe 45', or is further carried through the second effect evaporator to rob it of its heat, it does not contaminate any condensed steam, nor is there any loss of said evaporated water in the procedure.

The condensate from the first effect apparatus 1 is carried by the pipe 4 to the lowest coils 60 of the second effect 54, which coils may be joined in series as shown, and said condensate is then drained off through the micrometer valve 61 and pipe 62 to the fresh water tanks.

66 represents a micrometer valve and 63 a drain to a trap, not shown, but which may be maintained at atmospheric pressure. 64 indicates a micrometer valve and 65 a pipe conveying high pressure steam to the pipe 55. The operation of this evaporating system will be clear from the foregoing but may be briefly summarized as follows:

Sea water being placed in the first effect evaporator 1, and in low pressure evaporator 54, high pressure steam, may be conveyed through the pipe 2 or auxiliary exhaust steam from donkey engines, or other auxiliary power plants, may be conveyed into said first effect evaporator through pipe 37. In either case, the micrometer valves 3 or 38 may be so adjusted that all the steam entering said evaporator 1 and passing through its coils 17, 18, 19, etc., will be condensed by the time it reaches the drain pipe 4, and further, the micrometer valve 5, in said pipe 4, may be so adjusted that any steam that may pass into said pipe will be throttled off. The hot fresh water thus produced is carried over to the second effect of low pressure evaporator 54 and through the coils 60, in order to abstract any surplus heat it may possess. From the coils 60 said condensate is drained off through the valve

61, and pipe 62, to the fresh water tanks. At no time is any fresh water condensate lost, nor is it ever contaminated with salt water vapor nor is a trap necessary for its recovery. In the meantime, it is evident that a maximum of heat is extracted from the original steam. In order to still further increase the efficiency of the system, all, or a portion of the vapor from the salt water in the first effect evaporator may be conducted through the pipe 48, the steam separator 50, the micrometer valve 52, and coils 17, 18, 19, etc., of the second effect evaporator to and through the valve 58. This said vapor thus evaporates an additional quantity of salt water in the low pressure apparatus 54, and at the same time, all the salt water condensate is saved, as above pointed out, by passing it through the pipe 59 to the distillers.

In addition to this salt water vapor auxiliary exhaust steam may be simultaneously, or independently used in said evaporator 54, by passing said auxiliary steam through the coils 17, 18, 19, etc., located on the right hand side of the partition 53, as seen in Figure 1, and located above said partition 53, as seen in Figure 2. Said auxiliary steam is conveniently introduced through pipe 55 and is so throttled by a micrometer valve 56 as to cause it to all be condensed by the time it reaches valve 66. If however any portion of it remains uncondensed when valve 66 is reached, said valve may be so adjusted as to throttle off the live steam, whereupon the condensed steam or water will pass through the pipe 63 to any convenient trap maintained at atmospheric pressure.

The partition 53, in the second effect evaporator prevents the condensates passing through the pipes 51 and 53, from mixing. Owing to its possible contamination with oil the condensate passing through the pipe 63 is not mixed with that passing through the pipe 62. Should it be desired to employ high pressure steam in the second effect evaporator, such may be introduced through the pipe 65, and valve 64, and in such case said second effect evaporator will operate in so far as its coils on the right hand side of the partition 53 are concerned in the same manner as does the first effect evaporator.

On the other hand, if it is desired to employ live steam simultaneously with the condensed vapor through pipe 51, it can also be employed that way. In other words, it will be observed that the second effect evaporator may be run independently, precisely as is the first effect evaporator, or it may be run simultaneously with the employment of vapor from the first effect evaporator through pipe 51.

It will now be clear that with the foregoing evaporator system, the following ad-

vantages contributing to its high efficiency are readily attained:

1. One is enabled to provide a relatively very long path of travel for the steam through the coils;

2. The micrometer valves afford a ready means for controlling the operation as well as the capacity of the system. In fact, the capacity of the system may be virtually controlled by the valves 3 and 38.

3. The drain plugs 30 constitute a means for draining off the condensate from each coil as it is formed so that only dry steam enters the coils. When desired, automatic float valves such as 70, see Figure 6, may be employed in connection with the openings 31, but in practice such valves are not found to be necessary in many cases.

4. The micrometer valves 5, 58 and 66 constitute a means for controlling the discharge of condensate from each group of coils, so that only condensed steam may escape from the coils, thus insuring a highly efficient heat exchange.

5. The pipe 4 constitutes a means for further abstracting heat from the condensate from the high pressure steam, and thus still further increases the efficiency of the apparatus;

6. The pipe 55 and partition 53 constitute a means for utilizing low pressure exhaust steam in the same apparatus that is utilizing low pressure vapor from said salt water;

7. The pipe 65 and partition 53 constitute a means of using high pressure steam in the same apparatus that is using low pressure vapor from salt water;

8. Owing to the relatively long coiled tubes, the high velocity of the steam, and to the micrometer valves insuring a complete condensation of the steam, the use of traps or drain pots may be done away with.

9. Owing to the continuously curved pipe in the coils, and the peculiar bracing and holding means preventing the bodily movement of said coils, the contractions and expansions incident to the changes in temperature greatly aid in keeping the coils free from scale.

10. It will be observed that the drain plugs 30 are omitted from the lowest row of coils in each evaporator, so that the lowest row of coils will conduct all the water that is condensed in the upper coils.

11. Further, it will be observed that the lowest row of coils may be arranged in series instead of in parallel as is illustrated in Figure 1.

12. This will expedite the further cooling of the condensate. In all cases, the doors 15, and their attached coils may be readily removed without disturbing the steam connections. Further, owing to the fact that the coils are unusually long, and owing to their peculiar curvature, the manufacturer is en-

abled to locate the ends of the coils in the plate 14 of each door farther apart than has been heretofore possible, with the same capacity of apparatus, and this results in the important advantage that when the end of the one coil is being expanded, it does not distort or change the dimensions of the hole, for the end of another coil.

13. In other words, the holes in the wall 14 accurately fit the coils even after repairs which is not the case when the holes are placed so near together that the expansion of a tube in one hole changes the dimensions of a neighboring hole.

14. Of course, although the coils have been shown as arranged in parallel, in each channel, yet they may be, if desired, arranged in series, or in any other connections which will best suit the requirements for cooling the condensed steam to a point where it may be discharged without the loss of vapor.

15. The graduations, not shown, on the disk 43, may be determined by a calibration made at various points with various portions of the slot 40 in the disk, for both water and steam. The micrometer valves in the steam pipes control the capacity of the evaporators while the said valves in the drain pipes control the pressure and temperature of the discharged condensates.

16. It is obvious that those skilled in the art may vary the details of the construction as well as the arrangement of parts without departing from the spirit of the invention, and therefore, we do not wish to be limited to the above disclosure except as may be required by the claims.

17. What is claimed is:

1. In an evaporator system the combination of a shell, adapted to contain the liquid to be evaporated; means comprising a coil, adapted to contain steam in said shell; a pair of channels located one above the other and provided with drains for passing a liquid by gravity from one into the other connected to said means; a pipe for conveying steam to said means; and a micrometer valve in said pipe adapted to so throttle said steam as to cause substantially all of it to condense in said channels before leaving said shell, substantially as described.

2. In an evaporator system the combination of a shell adapted to contain salt water; means to impart heat to said water comprising a plurality of coils of pipe adapted to receive steam; a plurality of channels located one above the other and provided with drains for passing liquid from one into the other connected to said means; a steam supply connected to said means; a drain pipe leading from said means; and a valve in said steam supply adapted to so throttle said supply as to cause substantially all of said steam to condense before entering said drain pipe, substantially as described.

3. In an evaporator system the combination of a shell adapted to contain salt water; means to impart heat to said water comprising a plurality of continuously curved coils of pipe adapted to receive steam; a pair of channels with which each coil is connected, said channels located one above the other and provided with drains; a steam supply connected to said means; a drain pipe leading from said means; a valve in said drain pipe; and a valve in said steam supply adapted to so throttle said supply as to cause substantially all of said steam to condense before entering said drain pipe, substantially as described.

4. In an evaporator system the combination of a shell adapted to contain salt water; means to impart heat to said water comprising a plurality of channels and continuously curved coils of pipe adapted to receive steam; drains connecting said channels; a steam supply connected to said means; a drain pipe leading from said means; means to prevent the bodily movements of said curved coils of pipe during changes of temperature but readily permitting changes in the curvature of said pipe; and a valve in said steam supply adapted to so throttle said supply as to cause substantially all of said steam to condense before entering said drain pipe, substantially as described.

5. In an evaporator system, the combination of a shell adapted to contain salt water; a pipe to convey away the vapors of said water; means to impart heat to said water comprising a plurality of coils of pipe adapted to receive steam; a pair of channels located one above the other provided with drains joined to each of said coils; a steam supply connected to said means; a drain pipe leading from said means; a second shell adapted to contain salt water; evaporating means in said second shell; a connection between said first named pipe and said second shell; a connection between said drain pipe and said second shell; and a micrometer valve in said steam supply adapted to so throttle said supply as to cause substantially all of said steam to condense before entering said drain pipe, substantially as described.

6. In an evaporator system the combination of a first effect evaporator; a steam supply for said evaporator; a valve in said steam supply; a drain pipe for the condensed steam; a valve in said pipe; means for conveying off the vapors formed in said evaporator; a second effect evaporator; connections provided with a micrometer valve between said means and said second effect evaporator; and connections between said drain pipe and said last named evaporator, substantially as described.

7. In an evaporator system the combination of a first effect evaporator comprising a plurality of evaporating coils; a plurality

of channels located one above the other with which said coils are connected; drains leading from the supply channels to the lower channels; a steam supply for said evaporator; a micrometer valve in said steam supply; a drain pipe for the condensed steam; a micrometer valve in said pipe; means for conveying off the vapors formed in said evaporator; a second effect evaporator comprising a plurality of sets of evaporating coils; connections provided with a micrometer valve between said means and one set of coils in said second effect evaporator; connections between said drain pipe and said last named evaporator; and means to supply steam to another set of coils in said second effect evaporator, substantially as described.

8. In an evaporator system, the combination of a first effect evaporator; a steam supply for said evaporator; a drain pipe for the condensed steam; a pipe to lead off the water evaporated; a second effect evaporator; two sets of coils in said last named evaporator; means to convey a portion of said evaporated water through one of said sets of coils; means to convey steam through another of said sets of coils; and means to connect said drain pipe to said second effect evaporator, substantially as described.

9. In an evaporator system the combination of a first effect evaporator; a steam supply for said evaporator; a micrometer valve in said supply; a drain pipe for the condensed steam; a micrometer valve in said pipe; a pipe to lead off the water evaporated; a second effect evaporator; two sets of coils in said last named evaporator; means to convey a portion of said evaporated water through one of said sets of coils; a micrometer valve in said means; means to convey steam through another of said sets of coils; a micrometer valve in said last named means; and means to connect said drain pipe to said second effect evaporator, substantially as described.

10. In an evaporator system the combination of an evaporator comprising a plurality of channels located the one above the other and provided with drains adapted to pass liquid from an upper to a lower channel; means to supply high pressure steam to said evaporator; independent means to supply low pressure steam to said evaporator; and a micrometer valve in each of said steam supplying means adapted to so throttle the steam as to cause substantially all of it to condense before leaving the evaporator, substantially as described.

11. In an evaporator system the combination of an evaporator; means to supply high pressure steam to said evaporator; independent means to supply low pressure steam to said evaporator; a micrometer

- valve in each of said steam supplying means adapted to so throttle the steam as to cause substantially all of it to condense before leaving the evaporator; an independent means to supply hot vapors to said evaporator; a valve controlling said last named means; and means for preventing said vapors from mixing with the steam in said evaporator, substantially as described. 65
- 10 12. In an evaporating system, the combination of an evaporator provided with two sets of coils separated by a partition; means to supply high pressure steam to one of said sets of coils in said evaporator; independent means to supply low pressure steam to the same set of coils of said evaporator; a micrometer valve in each of said steam supplying means adapted to so throttle the steam as to cause substantially all of it to condense before leaving the evaporator; independent means to supply hot vapors to the other set of coils; and a micrometer valve controlling said last named means, substantially as described. 70
- 15 13. In an evaporating system, a coil having a continuous and reversed curve from end to end; and means to prevent changes in temperature from bodily moving said coil while permitting ready changes in curvature, whereby the cracking of any scale that may be formed therein is facilitated, substantially as described. 75
- 20 14. In an evaporating system, a coil having a continuous and reversed curve from end to end; means to prevent changes in temperature from bodily moving said coil while permitting ready changes in curvature, whereby the cracking of any scale that may be formed therein is facilitated; a channel 80 to which one end of said coil communicates; another channel with which the other end of said coil communicates; and means for admitting steam to said first named channel, substantially as described. 85
- 25 15. In an evaporator the combination of a plurality of channels located one above the other and each provided with a perforated drain plug; and steam coils each communicating with said channels in pairs, substantially as described. 90
- 30 16. In an evaporator the combination of a plurality of channels located one above the other and provided with depressions and each provided also with a draining means located in a depression; and steam coils communicating with said channels, substantially as described. 95
- 35 17. In an evaporator the combination of a plurality of channels located one above the other, and provided with draining means by which one channel drains into another; 100
- 40 an inspection opening closed by a plug located above said draining means; and steam coils communicating with said channels in pairs, substantially as described. 105
- 45 18. In an evaporator the combination of means for supplying steam; means for condensing said steam; channels located one above another in which said condensed steam collects; means for draining said condensed steam by gravity from one channel into another; and means for so throttling said steam as to cause it to be substantially all condensed before leaving the system, substantially as described. 110
- 50 19. In an evaporator the combination of means comprising a coil element; means for passing steam through said coil; a pair of channels located one above another to one of which each end of said coil is connected; means for draining by gravity liquid from one of said channels into the other; and means for so throttling said steam as to cause it to be substantially all condensed when it leaves the system, substantially as described. 115
- 55 20. In an evaporator the combination of a container for the liquid to be evaporated; a plurality of coil elements in said container; a plurality of channels located one above the other to which the ends of said coil elements are connected in pairs; drains from an upper channel into a lower channel; means to pass steam into said coil elements and channels; and means to draw off the liquid condensed in said channels, substantially as described. 120
- 60 21. In an evaporator the combination of means to supply steam; means to throttle said steam; means to separate at a plurality of points the condensed from the uncondensed steam as fast as it is formed; means to collect the condensed steam from all of said points; and means to draw off the condensate thus collected, substantially as described. 125
- 65 22. In an evaporator the combination of a container for the liquid to be evaporated; means to heat said liquid comprising a plurality of coil elements located one above the other; means to supply steam to said elements in series; means to segregate the steam condensed in said first named means at a plurality of points located one above the other; means to drain all of the condensate to a single point; and means to draw said condensate from the system, substantially as described. 130
- 70 In testimony whereof we affix our signatures.

CHARLES W. DYSON.
MILTON C. STUART.
